FOLDING CRATE.

1,012,366.

Specification of Letters Patent. Patented Dec. 19, 1911.

Application filed February 9, 1911. Serial No. 607,526.

To all whom it may concern:

Be it known that I, JOHN HENREY KIDWELL, a citizen of the United States of America, residing at Pittsburgh, in the county of Allegheny and State of Pennsylvania, have invented certain new and useful Improvements in Folding Crates, of which the following is a specification, reference being had therein to the accompanying drawing.

This invention relates to folding crates, and the objects of my invention are, first, to provide a crate that can be advantageously used for shipping poultry, fruit and various kinds of merchandise; second, to provide a crate consisting of comparatively few parts that can be folded and collapsed to occupy a comparatively small space in storage or transportation; third, to furnish a folding crate with novel means for maintaining it rigid when in a set up position, and fourth, to accomplish the above results by a mechanical construction that is simple, durable and inexpensive to manufacture.

With the above and other objects in view, the invention consists of the novel construction, combination and arrangement of parts to be hereinafter specifically described and then particularly claimed.

In describing the invention in detail, reference will be had to the accompanying drawings, wherein like numerals of reference designate corresponding parts throughout the several views, in which:—

Figure 1 is a perspective view of the crate in a set up position, Fig. 2 is a longitudinal sectional view of the crate in a folded position, Fig. 3 is a cross sectional view of the same, taken on the line III—III of Fig. 2, Fig. 4 is a perspective view of the crate in a folded position, and Fig. 5 is a longitudinal sectional view of a portion of the crate.

A crate in accordance with this invention comprises a rectangular base plate having secured upon its upper face at each end thereof vertically disposed and transverse cleats 2 and further having secured to its upper face in proximity to the front and rear thereof vertically-disposed longitudinally-extending cleats 3. The cleats 2 are flush with the end edges of the base plate while the cleats 3 are flush with the side edges of said plate. The cleats 3 are of greater length than the cleats 2 and have their ends abutting against the ends of the

cleats 2. The cleats 3 are also of greater depth than the depth of the cleats 2 for a purpose which will presently appear.

The cleats 2 are slotted, as at 4 and pivotally mounted in said slots by rods 5 are the lower ends of vertical bars 6. The rods 5 extend longitudinally of the cleats 2 and pivotally support the bars 6, whereby said bars can be swung inwardly upon the base plate 1. The bars 6 have the inner sides thereof connected by transversely arranged slats 7 and 8, the slat 8 extending above the upper ends of the bars 6. The bars 6 and the slats 7 and 8 constitute the end walls of the crate, and the crate is of a sufficient length to permit of the end walls being swung inwardly with the free ends of said walls confronting each other upon the base plate.

The upper edges of the longitudinal cleats 3 adjacent to the ends thereof, are provided with two sets of slots 9, and pivotally mounted in said slots by longitudinal pins 10 are the lower ends of links 11, the pins 10 extending throughout the length of each cleat and the links 11 being arranged in sets. Pivotally mounted between the upper ends of the links of each set by pins 12 are the lower ends of single links 13, said single links having the upper ends thereof pivotally mounted in slots 14 provided therefor in the lower edges of the longitudinal rails 15 of a rectangular lid frame. The side rails 15 of the lid frame have the ends thereof connected by end rails 16 of less depth than the longitudinal rails 15, and hinged to the outer edge of one of the longitudinal rails 15 is a lid 17 adapted to close the rectangular frame.

The upper ends of the single links 13 are pivotally retained within the slots 14 by pins 18 extending throughout the length of each of the rails 15, and the pins 12 connecting the links 11 and 13 are of a sufficient length to extend from one set of links 11 to the other set.

The set of links 11 have the inner sides thereof provided with longitudinal slats 19 and the single links 13 are connected upon the inner sides by longitudinal slats 20, the slats 19 and 20 coöperating with the slats 7 of the end walls in forming the framework of the crate.

After the end walls have been folded inwardly, the side walls of the crate can be collapsed by the sets of links 11 folding in-

wardly and the single links 13 folding outwardly, thereby allowing the lid frame to rest upon the upper edges of the longitudinal cleats 3, and with the lid 17 in a closed position the crate forms a compact parcel.

5 The lower ends of the bars 6 of the end walls and the ends of the links 11 and 13 are rounded, whereby the crate can be easily collapsed, and in some instances, additional links 11 and 13, as shown in dotted 10 lines, Fig. 1, can be employed when the side walls of the crate are of considerable length.

To place the collapsed crate in a set up 15 position, it is necessary to open the lid 17, raise the lid frame and then the end walls. As the end walls are swung to a vertical position, the ends of the slats 7 engage the 20 inner sides of the slats 19 and 20 and there- by brace and prevent accidental collapse of the side walls. The vertical position of the end walls is determined by the slats 8 con- 25 tacting with the end rails 16 of the lid frame, the upper ends of the bars 6 riding under the end frames 16, as best shown in Fig. 5 of the drawings.

The crate in its entirety can be made of light and durable wood, and while in the drawings there is illustrated a preferred 30 embodiment of the invention, it is to be understood that the structural elements thereof are susceptible to such changes as fall within the scope of the appended claim.

What I claim is:—

35 A folding crate comprising top and bottom members, each having a rectangular

contour and connected together at opposite sides by link constructions adapted to permit said members to be spaced apart or be in close proximity to provide an expanded or folded structure, said link constructions carrying slats on their inner faces, end members each comprising spaced-apart bars pivotally connected to the bottom frame member above the plane of the upper face of the bottom of the crate and intermediate and spaced from the planes of the inner faces of the side walls of the crate when in operative position and adapted to be folded inwardly between said members when in folded or collapsed position and slats secured to said bars and positioned to lie between corresponding slats of opposite link constructions to prevent, when in operative position, collapsing of the link structures inwardly, said bars being of a length to fit beneath and support the top member when in expanded position to retain the top and bottom members from relative collapsing, each of said end members also having a stop adapted to contact with the inner face of the ends of the top frame to prevent the end members from moving outwardly beyond an operative position, and a cover for the top frame.

In testimony whereof I affix my signature in the presence of two witnesses.

JOHN HENREY KIDWELL.
